CLAIM

The ornamental design for a drain template, as shown and described.

DESCRIPTION

FIG. 1 is a perspective view of the drain template of the present invention.

FIG. 2 is a top view of the drain template.

FIG. 3 is a bottom view of the drain template; and,
FIG. 4 is a side view of the drain template. The plate is round and the other side views are identical.

1 Claim, 4 Drawing Sheets

FIG. 1

FIG. 2

FIG. 3

FIG. 4
